DESIGN FOR A TEXTILE FABRIC

Application filed March 23, 1933. Serial No. 47,552. Term of patent 3½ years.

To all whom it may concern:

Be it known that we, JOHN WOLF and FRED W. KIEL, both citizens of the United States, residing at Lynbrook, county of Nassau, and New York city, county of New York, respectively, in the State of New York, together with ROBERT C. KAHRMANN, a citizen of the United States, and residing at Elizabeth, county of Union, in the State of New Jersey, have invented a new, original, and ornamental Design for a Textile Fabric, of which the following is a specification, reference being

had to the accompanying drawing, forming a part thereof.

The figure is a plan view of a portion of a textile fabric disclosing one complete unit of design.

We claim:

The ornamental design for a textile fabric as shown and described.

JOHN WOLF.
FRED W. KIEL.
ROBERT C. KAHRMANN.
